UNITED STATES PATENT OFFICE.

FRANK E. MILLER, OF PITTSBURGH, PENNSYLVANIA, ASSIGNOR TO PRESSED STEEL CAR COMPANY, OF PITTSBURGH, PENNSYLVANIA, A CORPORATION OF NEW JERSEY.

DOOR RELEASING AND LOCKING MECHANISM.

Application filed December 12, 1923. Serial No. 680,156.

To all whom it may concern:

Be it known that I, FRANK E. MILLER, a citizen of the United States, residing in Pittsburgh, in the county of Allegheny and State of Pennsylvania, have invented certain new and useful Improvements in Door Releasing and Locking Mechanism, of which the following is a specification.

This invention relates to railway dump cars and has for an object the provision of means for operating a plurality of discharge door supporting members and for locking such members in their supporting positions with the door when the door is closed.

Another object of the invention is to provide a dump car with novel means for locking a plurality of discharge door supporting members in supporting position with a discharge door of the car when the door is closed.

A further object of the invention is to provide a mechanism for operating a plurality of discharge door supporting and releasing members, which mechanism comprises a plurality of links operatively connected with said members and with each other, such links embodying means adapted to cooperate to lock said members in their door supporting positions.

Referring to the drawings in which like reference characters refer to like parts, Fig. 1 is a plan view of a portion of a railway dump car embodying the invention; Fig. 2 is a side elevational view of the same; Fig. 3 is an enlarged side elevational view of the same, showing the mechanism in its door releasing position; and Fig. 4 is an enlarged sectional view taken on the line 4—4 of Fig. 2.

Referring now in detail to the drawings, the reference character 1 indicates the side wall of a railway car, and 2 indicates the discharge doors which are preferably hinged to or adjacent the center sill 3 and having their free edges adjacent the side wall 1. Each of the doors 2 may be made of wood or metal and constructed in any preferred manner. Each of these doors is provided with strengthening members 4, each of which is preferably U-shaped in cross section for the greater part of its length and having a horizontal flange 5 which is secured to the door. These members extend outwardly beyond the free edge of the door 55 and preferably beyond the side wall 2 and

are adapted to be engaged by members 6 to support the door in closed position. The outer end portion of these members 4 instead of being U-shaped in cross section are provided with top portions 7 thus forming 60 sockets for the reception of a bar or other suitable door closing means.

The members 6 are spaced apart and adjacent their upper ends are pivotally connected with bracket members 8 which are 65 secured to the side wall 1. Each of the members 6 adjacent its lower end is provided with a ledge 9 the upper surface of which is adapted to engage with the lower surface of the outer end portion of one of the members 4 and when in such position will support the door in closed position. The pivot points of the members 6 are so located that these members will, after they have been moved out of engagement with the members 75 4, move by gravity to their proper door supporting positions. There are preferably two members 6 for each discharge door, which members are spaced apart and when operated preferably move in opposite directions. 80 Between these members a stationary member 10 is preferably provided which is secured to the side wall 1 and is provided with a T-shaped projection 11 on which a member 12 is slidably mounted. This member 85 12 is provided with a T-shaped opening 13 which is adapted to receive the projection 11 and when the members are in their operative positions it will be noted that they will be so interlocked that they will not become 90 accidentally separated and yet free movement of the member 12 relative to the member 10 will be permitted. The member 12 is provided with a projection 14 on which the adjacent inner end portions of links 15 and 95 16 are loosely mounted, the outer end portion of each link being loosely connected with one of the members 6. The member 12 is also provided with stop shoulders 17 which are adapted to engage with stop shoulders 100 18 formed on the member 10 to prevent the member 12 from moving downwardly an excessive distance.

The link 16 between its ends is provided with a downwardly projecting portion 19 on 105 which a locking cam 20 is pivotally mounted, which cam is adapted to engage a projection 21 on the link 15 to lock the members 6 in their door supporting positions. Below the cam 20 the portion 19 of the link 110

16 is preferably provided with an outwardly extending portion 22 which forms a striking block which may be struck with a sledge or other suitable tool to open the door.

- 5 Assuming the door to be in closed position and the members 6 locked in their door supporting positions, as illustrated in Figs. 1, 2 and 4, and it is desired to open the door, the operator moves the cam 20 out of engagement with the projection 21 and then strikes the portion 22 of the link 16 an upward blow with a sledge or other suitable tool which causes the links 15 and 16 and member 12 to move upwardly which causes 10 the members 6 to move out of their door supporting positions, as shown in Fig. 3 of the drawings and thus permits the door to drop. As soon as the door has been released the members 6 will move automatically into 15 their door supporting positions, the links 15 and 16 also moving automatically with the members to their proper operative positions as shown in Fig. 2 of the drawings.

When it is desired to close the door the 20 operator inserts a bar or other suitable device in the end portion of one of the strengthening members 4 and by the use of such bar raises the door until the tops 7 of the members engage the bevelled surfaces 23 25 with which the lower portions of the members 6 are provided and as the pivots between the members 6 and 15, 16 are below the pivot between the members 6 and 12 a continued upward movement of the door 30 will cause the members 6 to move toward each other and out of the path of travel of the ends of the members until such time as the door is closed at which time the members 6 will move by gravity to their door supporting positions as illustrated in Fig. 1 35 after which the operator moves the cam 20 from its inoperative position as illustrated in Fig. 3 to its operative position in engagement with the projection 21 on the link 15 40 thus locking the members 6 in their door supporting positions. It will be noted that as the member 12 and inner ends of the links 15 and 16 are moved upwardly the distance between the pivotal point of the cam 20 and 45 the face of the projection 21 becomes less, thus when the cam 20 is in engagement with the projection 21 any tendency of the links 15 and 16 to move upwardly, will be resisted by the cam and projection.

50 It will be apparent to those skilled in the art to which this invention appertains that changes in the form and arrangement of the several parts forming the invention may be made without departing from the spirit and 55 scope of the appended claims.

Having thus described the invention what I claim as new and desire to secure by Letters Patent is:—

- 60 1. In a dump car, a discharge door, a plurality of members movable into and out of

supporting positions with said door, links for operating said members, and locking means carried by said links for locking said members in their supporting positions with 70 said door.

2. In a dump car, a discharge door, members movable into and out of supporting positions with said door, links connected with said members, and members carried by said links adapted to cooperate to lock said members in their supporting positions with said door.

3. In a dump car, a discharge door, members movable into and out of supporting positions with said door, links connected with 80 said members, and means loosely mounted on one of said links adapted to engage the other of said links to lock said members in their supporting positions with said door.

4. In a dump car, a discharge door, members movable into and out of supporting positions with said door, means for operating said members, and cam means on the first mentioned means for locking said members 85 in their supporting positions with said door.

5. In a dump car, a discharge door, members movable into and out of supporting positions with said door, links connected with said members for operating said members and cam means carried by said links for 90 locking said members.

6. In a dump car, a discharge door, members movable into and out of supporting positions with said door, links pivotally connected with said members and with each 100 other, and cam means below the pivotal connection between said links adapted to lock said members.

7. In a dump car, a discharge door, members movable into and out of supporting 105 positions with said door, a plurality of connected links for operating said members, locking members carried by said links adapted to cooperate to lock said members in their door supporting positions.

8. In a dump car, a discharge door, members movable into and out of supporting positions with said door, a vertically movable member between said members, connections from said members to said vertically movable member, and means on said connections adapted to lock said members in their supporting positions with said door.

9. In a dump car, a discharge door, a plurality of members movable into and out of supporting positions with said door, links pivotally connected with said members, joints between said links and members, a locking member on each of said links below 120 said joints, said members being adapted to cooperate to lock said members in their door supporting positions.

10. In a dump car, a discharge door, members movable into and out of supporting positions with said door, a connection from 125

one of said members to the other for operating said members, said connection being jointed between said members, and locking members below the joint between said members adapted to lock said members in their supporting positions with said door.

11. In a dump car, a discharge door, members pivotally mounted on said car adapted to be moved into and out of supporting positions with said door, a jointed connection extending between said members for operating said members, and cam means for locking said members in their supporting positions with said door, said cam means extending in 15 the direction of the joint in said connection.

12. In a dump car, a discharge door, members movable into and out of supporting positions with said door, links connected with said members and with each other for operating said members, and means on said links located below the connection between said links adapted to cooperate to lock said members in their supporting positions with said door.

13. In a dump car, a discharge door, door supporting and releasing members pivotally mounted on said car, a stationary guide member on said car between said door supporting and releasing members, a slidable member 25 on said stationary member, links connecting said door supporting and releasing members and said slidable member, and means on said members adapted to cooperate to lock said door supporting and releasing members 30 in their door supporting positions.

14. In a dump car, a discharge door, members movable into and out of supporting positions with said door, links connecting said members, said links being loosely connected together at their adjacent ends, a downwardly depending portion on one of said links, an outwardly extending projection on the other of said links, and a member pivotally mounted on said downwardly depending portion adapted to engage said projection to lock said members in their supporting 40 positions with said door.

15. In a dump car, a discharge door, members movable into and out of supporting positions with said door and means for operating said members, said means comprising a plurality of operatively connected links, and means on said links below the connection between said links adapted to lock said members in their supporting positions with said 50 door.

16. In a dump car, a discharge door, members movable into and out of supporting positions with said door, means for operating said members, said means having a joint located between said members and means on said operating means adapted to cooperate below said joint to lock said members in their supporting positions with said door.

In testimony whereof I affix my signature 65 in the presence of two witnesses.

FRANK E. MILLER.
